(57) **CLAIM**

The ornamental design for a frontload drying appliance, as shown and described.

DESCRIPTION

FIG. 1 is a first top perspective view of the frontload drying appliance of the present invention;

FIG. 2 is a second top perspective view of the frontload drying appliance of the present invention;

FIG. 3 is a top plan view of the frontload drying appliance of the present invention;

FIG. 4 is a bottom plan view of the frontload drying appliance of the present invention;

FIG. 5 is a first side elevation view of the frontload drying appliance of the present invention;

FIG. 6 is a second side elevation view of the frontload drying appliance of the present invention;

FIG. 7 is a third side elevation view of the frontload drying appliance of the present invention; and,

FIG. 8 is a fourth side elevation view of the frontload drying appliance of the present invention.

The broken lines in the figures are for contextual purposes or show the environment and form no part of the claimed design.
